DELICATESSEN TRAY FOR SERVING AND
PRESENTING FOOD

Lee A. Whitten, 2658 Ivanhoe Drive,
Los Angeles, Calif. 90039

Filed Apr. 26, 1974, Ser. No. 464,450

Term of patent 14 years

Int. Cl. D7—01, 99

U.S. Cl. D7—27

Fig. 1.

Fig. 2.

Fig. 3.

Fig. 4.

FIG. 1 is a perspective view of a delicatessen tray for serving and presenting food showing my new design;

FIG. 2 is a front elevation view;

FIG. 3 is a bottom view indicated at arrow III of FIG. 2; and

FIG. 4 is a cross-sectional view taken along the plane of IV—IV in FIG. 3, thereof.

I claim:

The ornamental design for a delicatessen tray for serving and presenting food, as shown.
